UNITED STATES PATENT OFFICE

115,724

DESIGN FOR A TEXTILE FABRIC

Louis Bry, New York, N. Y.

Application May 24, 1939, Serial No. 85,178

Term of patent 3½ years

To all whom it may concern:

Be it known that I, Louis Bry, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein

The figure is a plan view of a piece of textile fabric showing my new design.

The design comprises a fabric, box-like in appearance, and is composed of fancy warp yarn

consisting of sequentially arranged looped wool yarns, and at spaced intervals therewith wool and mohair twist yarns; said twist yarn having alternate knobs of mohair and wool, and a weft comprising wool nub yarn, fancy wool loop yarn and fancy nub yarn arranged at intervals, the combination of these warp and weft yarns giving a variegated box appearance.

I claim:

The ornamental design for a textile fabric, substantially as shown and described.

LOUIS BRY.
